US00D803820S

(12) **United States Design Patent** (10) **Patent No.:** **US D803,820 S**
(45) **Date of Patent:** **** Nov. 28, 2017**

(54) **PORTABLE ELECTRONIC DEVICE**

(71) Applicant: **HTC Corporation**, Taoyuan (TW)

(72) Inventors: **Daniel Hundt**, San Francisco, CA (US); **Claude Zellweger**, San Francisco, CA (US); **Catherine Sayim Kim**, San Francisco, CA (US); **Lawrence Herman Fong**, San Francisco, CA (US); **Tanatip Arunanondchai**, San Francisco, CA (US); **Hannes Jens Dieter Harms**, San Francisco, CA (US); **Benjamin Scott Avery**, San Francisco, CA (US); **Mathias Andreas Hintermann**, San Francisco, CA (US)

(73) Assignee: **HTC Corporation**, Taoyuan (TW)

(**) Term: **15 Years**

(21) Appl. No.: **29/553,944**

(22) Filed: **Feb. 5, 2016**

(51) LOC (10) Cl. **14-03**

(52) U.S. Cl.

USPC **D14/248**

(58) **Field of Classification Search**

(57) **CLAIM**

The ornamental design for portable electronic device, as shown and described.

DESCRIPTION

FIG. 1 is a front perspective view of a portable electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines which show portions of a portable electronic device form no part of the claimed design.

1 Claim, 7 Drawing Sheets
